DESCRIPTION

U.S. PATENT DOCUMENTS

FIG. 1 is a front perspective view of the metal clad/armored clad electrical cable to electrical enclosure electrical transition fitting housing of my design;

2,195,933 A 4/1940 Marlborough et al.
D187,594 S 4/1960 Stover
D187,792 S 5/1960 Stover
2,962,542 A 11/1960 Witt
3,187,088 A 6/1965 Warner
3,411,163 A 11/1968 Myers

FIG. 2 is a right side view thereof;

FIG. 3 is a left side view thereof;

FIG. 4 is a top view thereof;

FIG. 5 is a bottom view thereof;

FIG. 6 is a front view thereof;

FIG. 7 is a rear view thereof; and,

FIG. 8 is a right side view thereof, shown in environmental use.

The broken lines shown represent unclaimed subject matter and form no part of the claimed design.
